FIG. 12.

FIG. 13

FIG. 1 is a side elevation of a mixer for liquids or the like embodying my new design;

FIG. 2 is a front elevation thereof;

FIG. 3 is a rear elevation thereof;

FIG. 4 is a top plan view thereof;

FIG. 5 is a front elevation of a modified form of the design, as shown in FIG. 1;

FIG. 6 is a rear elevation thereof, as shown in FIG. 5;

FIG. 7 is a side elevation thereof, as shown in FIG. 5;

FIG. 8 is a top plan view thereof, as shown in FIG. 5;

FIG. 9 is a side elevation of a modified form of the design, as shown in FIG. 1;

FIG. 10 is a rear elevation thereof, as shown in FIG. 9;

FIG. 11 is a front elevation thereof, as shown in FIG. 9;

FIG. 12 is a top plan view thereof, as shown in FIG. 9; and

FIG. 13 is a top plan view of a modified form of the design, as shown in FIG. 1, wherein the only differences thereover are seen in the plan view, as shown and,

The coupling guard and the electric motor shown in broken lines are for illustrative purposes only.

I claim:

The ornamental design for a mixer for liquids or the like, substantially as shown and described.
